UNITED STATES PATENT OFFICE.

EMIL IBACH, OF PHILADELPHIA, PENNSYLVANIA, ASSIGNOR TO BUDD WHEEL CORPORATION, OF PHILADELPHIA, PENNSYLVANIA, A CORPORATION OF VIRGINIA.

HUB-CAP-LOCKING DEVICE.

1,391,118.

Specification of Letters Patent. Patented Sept. 20, 1921.

Application filed September 1, 1917. Serial No. 189,274.

To all whom it may concern:

Be it known that I, EMIL IBACH, a citizen of Germany, who have declared my intention to become a citizen of the United States, 5 residing at Philadelphia, in the county of Philadelphia, State of Pennsylvania, have made a certain new and useful Invention in Hub-Cap-Locking Devices, of which the following is a specification.

10 This invention relates to hub cap locking devices.

The object of the invention is to provide hub cap-locking devices which are simple, economical to manufacture, and efficient in 15 operation.

Another object of my invention is to provide a locking device for a hub cap which is housed within the nut and so mounted that no openings are left through which dirt and 20 moisture can get into the interior of the hub.

Another object of this invention is to provide a hub cap-locking device which is so constructed that the latch will be automatically retracted when the hub-cap is screwed 25 into place by hand.

A further object of the invention is to provide means for locking the detachable wheel upon its carrying hub, the locking means being released by the application of a 30 spanner or other suitable tool to release the clamping nut.

Further objects of the invention will appear more fully hereinafter.

The invention consists substantially in 35 the construction, combination, location, and relative arrangement of parts, all as will be more fully hereinafter set forth, as shown in the accompanying drawing, and finally pointed out in the appended claims.

40 Referring to the drawing:—

Figure 1 is a view in end elevation partly in section taken on the line 1, 1, Fig. 2, and looking in the direction of the arrows of a hub structure embodying my invention.

45 Fig. 2 is a sectional view taken on the line 2, 2, Fig. 1, and looking in the direction of the arrows.

Fig. 3 is a broken detail view similar to Fig. 1 showing the locking means of a right 50 hand wheel.

Fig. 4 is a plan view of a wrench or spanner employed in accordance with my invention.

Fig. 5 is a sectional view taken on the line

5, 5, Fig. 4, looking in the direction of the 55 arrows.

Fig. 6 is a sectional view taken on the line 6, 6, Fig. 4, and looking in the direction of the arrows.

The same part is designated by the same 60 reference numeral wherever it appears throughout the several views.

In structures of vehicle wheels such as are employed extensively in connection with 65 motor vehicles, and particularly with wheels of the wire spoke type it is desirable to provide means by which the wheel may be readily detachable and removable from its hub and quickly and easily applied thereto, and securely clamped in place in such manner as to be locked in position when applied.

It is also desirable to provide means to prevent the accidental disengagement or release 70 of the locking means employed by reason of the backing off of the clamping nut usually employed in connection with locking devices, through jolts, shocks, or otherwise.

It is also desirable to provide a hub structure for detachable or demountable wheels 75 which is simple, economical to manufacture and efficient in operation. It is among the special purposes of my present invention to

provide a hub structure for detachable demountable wheels which secures the advantages and desirable characteristics referred 80 to by means of the characteristic features of construction as will be more fully herein-

after set forth.

Referring to the drawing: Reference numeral 1 designates the outer shell which 90 forms a part of the wheel proper. The hub cap 2 which in the form shown is preferably made in two pieces of pressed steel suitably secured together is provided with interior

threads 3 adapted to screw on coöperating 95 threads of the hub shell not shown, but which is well known in the art. The outer shell 1 is flared outwardly at 4 to form a

pocket 6 extending circumferentially around the hub cap 2 in which is located a stop plate 100 7 provided with teeth 8 which forms part of

the locking mechanism. In the outer shell of the hub cap 2 is located a slot 9 at right angles to the face of the hub cap. A brass

safety latch 10 provided with a tooth 11 is 105 located in this slot and is pivoted at the rear end of said slot or at a point farthest

from the face of the hub cap as indicated at

12. At the front of the latch is a lug extension 13 which is rounded to receive the wrench pin as will be more fully hereinafter explained. The hub cap is provided with 5 two holes 17 and 18 to receive the wrench pins 28 of the wrench 29. A rounded spring 30 is secured to the latch 10 and is anchored in the hub cap to normally force the same outwardly from the center of the 10 hub cap so that the tooth 11 is projecting into the pocket 6 formed by the outer shell 1 to thereby engage teeth 8 of the stop plate 7. When the pin 28 of the wrench 29 enters the hole 17 it engages the projection 13 of 15 the latch 10 causing same to rock about its pivot 12 thereby bringing the projecting portion 11 of the latch 10 flush with the outer surface of the hub cap and out of engaging relation with the stop plate 7, thus 20 permitting the cap to be removed as will be readily understood. When the wrench is removed it is obvious that the spring 30 will again force the latch into its locking position as shown in Fig. 2. As stated I prefer 25 to make this latch of brass, and the advantages secured by this structure are apparent. When the latch is seated in the slot in its locking position it can not be injured by pressure on the stop plate teeth as the sides 30 of the slot tend to hold it in position, and the pressure on the latch is transmitted to the side of the slot rather than against the pivot pin of the latch. It is apparent with 35 this structure that the wrench is not needed in starting the cap on the hub as the top of the latch is depressed by engaging with the edge of the opening on the outer hub shell as the hub cap is turned on. It will also be seen that I provide in this structure a surface contact between the safety latch and 40 the teeth of the stop plate as distinguished from the line contact where the pivotal movement of the safety latch relative to the stop plate is in a plane parallel to the end 45 surface of the hub cap.

It will be noted that the hub cap, 2, is so positioned with respect to the hub, 1, that the convex end face, 4, of the hub forms 50 substantially a continuous surface with the end face of the hub cap. In other words, the end face of the hub cap is substantially flush with the end face of the hub. Whenever, in this specification or claims, I use 55 the term "flush" with reference to the relative positions of two surfaces, I mean that said surfaces are so positioned relative to each other as to form, in appearance, a substantially continuous surface, as, for instance, in this embodiment, the convex end 60 face of the hub cap, 2, forms, in appearance a substantially continuous surface with the end face, 4, of the hub 1.

Having now set forth the object and nature 65 of my invention and having shown and described a structure embodying the char-

acteristic features thereof, what I claim as new and useful and of my own invention, and desire to secure by Letters Patent, is,—

1. A device of the class described comprising the combination of inner and outer hubs, 70 a hub cap detachably fitted on one of said hubs to hold the two hubs together, the side wall of said hub cap having a slot formed therein, a latch pivotally mounted in said hub cap and swinging in a plane radial to the axis thereof, said latch having a tongue 75 projecting through said slot and a cam surface, a keeper member on one of said hubs in line with said tongue, the face of said cap being provided with a pair of holes, one of 80 which is in line with said cam surface.

2. In a device of the class described, the combination of inner and outer hubs, said outer hub being removably mounted on said inner hub, a hub cap screwed on one of said 85 hubs and engaging the other to hold the two hubs together, the side wall of said hub having a slot formed therein, a latch pivotally mounted in said hub cap and swinging in a plane radial to the axis thereof, said latch being pivoted to said hub cap at its forward end and having a tongue projecting through said slot and a cam surface, a keeper member mounted on one of said 90 hubs in line with said tongue, the face of said cap being provided with a hole in line with said cam surface and adapted to accommodate means for engaging said surface to rock said latch on its pivot.

3. In a device of the class described, the 100 combination of an inner hub, an outer hub removably mounted thereon, a hub cap detachably and removably mounted on one of said hubs and engaging the other hub to hold said hubs together, said hub cap having 105 a slot formed in the side wall thereof, a latch pivoted at its forward end in said hub cap and having a cam surface at its rear end, said latch swinging in a plane radial to the axis of said hub cap and having a 110 tongue projecting from its central part through said slot, a keeper member on one of said hubs in line with said tongue, and means adapted for rocking said latch.

4. In a device of the class described, the 115 combination of an inner hub, an outer hub removably mounted thereon, a hub cap screwed on one of said hubs and engaging the other to hold the two in engagement, said hub cap having a slot in its side wall 120 lying in a plane radial to the axis thereof, a latch housed in said hub cap and pivoted at its forward end thereto, said latch having a tongue extending through the slot in said side wall and a laterally extending arm 125 at its rear end, provided with a cam surface adapted to be engaged by a wrench applied to rotate the hub cap, and a keeper member mounted on one of said hubs in line with said tongue.

5. In a device of the class described, the combination of an inner hub, an outer hub removably mounted thereon, a hub cap screwed on one of said hubs and engaging 5 the other to hold the two in engagement, said hub cap having a slot in its side wall lying in a plane radial to the axis thereof, a latch pivotally mounted in said hub cap at its forward end and having a tongue extending through the slot of said hub cap, and a laterally extending arm having a cam surface, the forward edge of said tongue being beveled, and a keeper member mounted 10 on one of said hubs in line with said tongue.
6. In a device of the class described, the combination of an inner hub, an outer hub removably mounted thereon, a hub cap screwed on the inner hub and engaging the 15 outer hub to hold the two hubs in engagement, said hub cap having a slot extending in a plane radial to the axis thereof, a latch pivoted at its forward end in said hub cap and swinging in said radial plane, said latch having a tongue extending through said slot and a keeper member mounted on said outer hub in line with said tongue.
7. In a device of the class described, the combination of an inner hub, an outer hub 20 removably mounted thereon, a hub cap formed of two telescoping sleeves, the forward ends of said sleeves being secured together and the rear parts thereof being spaced apart to form a chamber between the 25 two sleeves, said inner sleeve being screwed on the inner hub and said outer sleeve having a bearing against the outer hub to removably hold the same in place on the inner hub, and a latch disposed in the chamber 30 between said sleeves and coöperating with a keeper on said outer hub to lock said hub cap against rotation on said inner hub.
8. In a hub structure, the combination with a hub shell and an outer shell, of a 35 hub cap adapted to fit on the hub shell to hold said outer shell thereon, and provided with a slot therein at right angles to the plane of the face of said cap, a stop plate carried by said outer shell to extend circumferentially around said cap in the plane of 40 the forward end of said slot, a latch pivotally mounted at its end in the rear end of said slot, and provided with a portion adapted to extend out of said slot into engaging
- relation with said stop plate, and an angularly projecting portion at its free end, 55 said cap being provided with a pair of holes, one of said holes being positioned opposite the angular portion of said latch, substantially as and for the purpose described.
9. In a device of the class described, the combination with an outer hub and an inner hub, of a hub cap formed of two telescoping cup-shaped members secured together at 60 their bottoms, said inner cup shaped member being threaded to screw on the inner hub and said outer cup-shaped member bearing against the outer hub to removably hold it in place, said outer cup-shaped member having its edge crimped over the end of said inner member.
10. In a hub structure, the combination with an outer shell, of a hub cap formed in two telescoping sleeves secured together, said inner sleeve adapted to screw on a hub, 65 and said outer sleeve bearing against said outer shell to removably hold the same in place, said outer sleeve being crimped at its inner end over the inner end of said inner sleeve, and a latch disposed between said 70 sleeves to lock said cap in place.
11. In a device of the class described, the combination of an inner hub, an outer hub removably mounted thereon, a hub cap detachably mounted on one of said hubs and 75 engaging the other hub to hold said hubs together, said hub cap having a slot formed in the side wall thereof, a latch pivoted at its forward end in said hub cap and swinging in a plane radial to the axis of said hub 80 cap, said latch having a portion projecting through said slot, a keeper member on one of said hubs in line with said portion, and means for rocking said latch.
12. In combination with the hub of a wire 85 wheel, a cap for said hub with its face substantially flush with the end face of the hub, a locking device carried by said cap and accessible at its face and housed by said hub, and means for normally holding the locking device in locking position, said locking device being such as to enable it to be 90 maintained in locking position during the operation of the wheel by centrifugal force.
- In testimony whereof I have hereunto set 95 my hand on this 7th day of August A. D., 1917.

EMIL IBACH.
